Specification for Design.

Patented May 10, 1921.

Application filed October 28, 1920. Serial No. 420,298. Term of patent 7 years.

To all whom it may concern:

Be it known that I, CLARENCE A. KLINE, a citizen of the United States, residing at San Francisco, in the county of San Francisco and State of California, have invented a new, original, and ornamental Design for Tire-Treads, of which the following is a specification, reference being had to the accompanying drawing, forming part thereof.

Figure 1 is a perspective view of the tire and Fig. 2 is an enlarged top plan view of a portion of the tire, both showing my design.

I claim:

The ornamental design for a tire tread, as shown.

CLARENCE A. KLINE.
